UNITED STATES PATENT OFFICE.

LOUIS STEINBERGER, OF NEW YORK, N. Y.

SUSPENSION-FIXTURE.

SPECIFICATION forming part of Letters Patent No. 735,613, dated August 4, 1903.

Application filed February 2, 1903. Serial No. 141,565. (No model.)

To all whom it may concern:

Be it known that I, LOUIS STEINBERGER, a citizen of the United States, and a resident of the city of New York, borough of Brooklyn, in the county of Kings and State of New York, have invented a new and Improved Suspension-Fixture, of which the following is a full, clear, and exact description.

My invention relates to a suspension-fixture to be used in overhead-line construction for electric railways, and more particularly as a device capable of serving as a turnbuckle, a strain, and a clip-support.

Heretofore in supporting trolley-wires and electric cables it has been customary to employ separate devices to accomplish the three purposes mentioned—that is to say, turnbuckles are used for lengthening and shortening the wires, strains are employed to effect electrical disconnection of one wire from another where the wires are mechanically connected, and a hanger or similar support is placed upon the span-wires for the purpose of supporting the clip.

To produce a device capable of serving in one or more of the capacities mentioned is the object of the present invention.

I do not limit myself to the particular structure herein shown, nor to a spherical form of the metallic frame portion, nor to the spherical outer insulated portion, nor to three extensions. Any other number may be used for certain purposes without departing from the spirit of my invention. This style of fixture may also be used with very good effect on curves and around corners.

Reference is to be had to the accompanying drawings, forming a part of this specification, in which similar characters of reference indicate corresponding parts in all the figures.

Figure 1 is a central vertical section through my combination suspension-fixture. Fig. 2 is a somewhat similar view showing in elevation certain portions of the clip-support and also showing the clip. Fig. 3 is a central vertical section upon the line 3 3 of Fig. 1 looking toward the left, and Fig. 4 is a front elevation of the annular metallic member 1 removed from the device.

A hollow member 1, of a general annular form and preferably having the particular

conformity of a sphere mutilated by a central cylindrical passage 2 and by substantially flat faces 3, 4, and 5, is removably fitted with sleeves 6 7 8 of insulation, provided integrally with flanges 6^a 7^a 8^a of the same material. The sleeves and flanges together constitute washers, as indicated in Figs. 1 and 2. Metallic sleeves 9 10 are provided with integral shoulders 11 12 and with threads 13 14 of opposite pitch, these threads being engaged by screw-bolts 15 16, provided, respectively, with left and right hand threads and with suspension-eyes 17 18. The washers 19 20, of insulating material, are made of annular form and are fitted against the shoulders 11 12. Revolvable nuts 21 22 are fitted upon the inner ends of the sleeves 9 10, which are threaded for the purpose, as indicated more particularly in Figs. 1 and 2. The inner ends of these sleeves are further provided with slots 23 24, which engage the insulation, thereby preventing the sleeves from turning.

A post 25 is provided with a threaded portion 26, upon which the clip 27 may be screwed. This post 25 is fitted against a washer 28 and is provided with a cylindrical portion 30^a and with a slot 30, the cylindrical portion 30^a being partially threaded and also being engaged by the nut 29, the slot 30 engaging the insulation 31, as above described with reference to the slots 23 24.

The annular portion 1 may be drop-forged or cast or may be formed by boring out a solid sphere of metal. The sleeves or washers 6 6^a 7 7^a 8 8^a are disposed radially, the same as the apertures in which they engage. The sleeves 9 10 are preferably in alignment with each other, as is usually the case with turnbuckle members.

The device is assembled as follows: The annular portion 1 being provided with its several apertures, as above described, the sleeves 9 10 and the post 25 are fitted with the washers 19, 20, and 28 and are inserted into position, the washers 6 6^a 7 7^a 8 8^a being inserted from the interior of the annular portion and the revolvable nuts 21, 22, and 29 being screwed firmly into position. By this means a complete turnbuckle is formed, the screw members 15 16 being free to rotate and to virtually lengthen and shorten the wire or

cable. The post 25, provided with its threaded portion 26, may be used as a handle for turning the spherical portion of the turn-buckle, as indicated in Fig. 1. The insulation is now applied in any approved manner, being preferably set by pressure.

When the device is used as a strain, the suspension-eyes 17 18 are turned in the screw-bolts 15 16 and are forced firmly against the bottoms of the sleeves 9 10, as indicated in Fig. 2. The screws being thus tightened, no relative movement of any part is permitted, and the device of course acts as a strain.

The device may be used as a clip-support whether the sleeves 9 10 and their accompanying parts are used as a strain or as a turn-buckle. A very good way to use the device is to first tighten the hanger-wires, as if using a turnbuckle, then force the screw-bolts 15 16 firmly into the position indicated in Fig. 2, whereby they become stationary, meanwhile using the post 25 as a handle for the purpose of rotating the spherical portion, and finally after securing the screw-bolts 15 16 firmly against the bottoms of the sleeves 9 10 the clip 27 is mounted upon the threaded portion 26.

Having thus described my invention, I claim as new and desire to secure by Letters Patent—

1. A suspension-fixture, comprising a metallic member of substantially annular form provided with an aperture, mechanism connected with said annular member and disposed upon opposite sides of said aperture for supporting said annular member, and insulated from same, and a clip-support provided with mechanism for engaging said aperture, said clip-support being insulated from said annular form.

2. A suspension-fixture, comprising a hollow metallic body member, turnbuckle mechanism engaging the same, and a clip-support engaging said hollow metallic body member and insulated therefrom.

3. A suspension-fixture, comprising a hollow metallic body member, turnbuckle mechanism engaging the same and insulated therefrom, and an insulated clip-support also engaging said hollow metallic body member.

4. A suspension-fixture, comprising a hollow metallic body member, means for supporting the same, and a clip-support engaging said hollow metallic body member and insulated therefrom.

5. A suspension-fixture, comprising a hollow metallic body member, insulated supports for the same, and a clip-support engaging said hollow metallic body member and insulated therefrom.

6. A suspension-fixture, comprising an insulated hollow metallic body member, turnbuckle mechanism engaging the same, and a clip-support also engaging said insulated hollow metallic body member.

7. A suspension-fixture, comprising an insulated hollow metallic body member, means

for supporting the same, and a clip-support engaging said insulated hollow metallic body member.

8. A suspension-fixture, comprising a turn-buckle mechanism provided with a revoluble member having a metallic portion, said metallic portion being provided with an aperture, and mechanism engaging said aperture and insulated therefrom for use as a turn-buckle-handle, or as a clip-support, as desired.

9. A suspension-fixture, comprising a turn-buckle mechanism provided with a metallic portion of substantially annular form, said portion of annular form being provided with radially-disposed apertures, and mechanism engaging said apertures and insulated therefrom for use as a turnbuckle-handle or as a clip-support, as desired.

10. A suspension-fixture, comprising an annular metallic member provided with a plurality of radially-disposed apertures, divers of which are arranged in alinement with each other, supporting members engaging said apertures thus arranged in alinement, and mechanism engaging another of said apertures and adapted for use either as a turnbuckle-handle, or as a clip-support.

11. A suspension-fixture, comprising an annular metallic member provided with a plurality of radially-disposed apertures, divers of which are arranged in alinement with each other, supporting members engaging said apertures thus arranged in alinement, hanger mechanism engaging said apertures thus arranged in alinement and insulated therefrom, and mechanism engaging other of said apertures and adapted for use either as a turnbuckle-handle or as a clip-support, as desired.

12. A suspension-fixture, comprising a metallic member of annular form, provided with apertures, tubular members provided with shoulders and disposed within divers of said apertures, insulating-washers of substantially annular form engaging said shoulders of said tubular members, and also engaging said metallic members for the purpose of insulating the same from said member of annular form, and mechanism engaging another of said apertures and free to support a clip.

13. A suspension-fixture, comprising a metallic revoluble member provided with apertures disposed in alinement with each other, tubular members disposed within said apertures and provided with threads, eyebolts provided with threads engaging said threads of said tubular members, and mechanism connected with said metallic member and serving as a clip-support or as a handle for actuating said revoluble member.

14. A suspension-fixture, comprising a revoluble member provided with apertures disposed in alinement of each other, tubular members disposed within said apertures and provided with threads of opposite pitch, eyebolts provided with threads engaging said threads of opposite pitch, means for insulat-

- ing said metallic revolute member from said tubular members, and mechanism connected with said revolute member and serving as a clip-support or as a handle for actuating said 5 revolute member.
15. A suspension-fixture, comprising a metallic revolute member provided with apertures, metallic turnbuckle mechanism engaging said apertures and insulated therefrom, 10 and a radially-disposed member mounted upon said tubular metallic revolute member and capable of use as a clip-support, or as a handle for rotating said revolute member.
16. A suspension-fixture, comprising a metallic revolute hollow member provided with apertures, metallic turnbuckle mechanism engaging said apertures and insulated therefrom, 15 and a radially-disposed member mounted upon said metallic revolute member and insulated therefrom, said radially-disposed member being capable of use either as a clip-support or as a handle for rotating said revolute metallic member.
17. A suspension-fixture, comprising an annular metallic member provided with means for supporting the same, and also provided with an aperture, a bolt provided with a shoulder and disposed within said aperture for supporting a clip, members of insulating material 20 engaging said aperture and said bolt, and locking members for preventing the withdrawal of said bolt from said aperture.
18. A suspension-fixture, comprising an annular metallic member provided with an aperture and with means for suspending said member, a bolt provided with a shoulder and disposed within said aperture for supporting a clip, insulating material engaging said aperture and said bolt, and a threaded nut disposed within said annular metallic member 25 and engaging said threaded bolt.
19. A suspension-fixture, comprising a metallic member of substantially annular form and provided with an aperture, means for supporting said metallic member, a bolt for supporting a clip, said bolt being provided with a shoulder and with a threaded portion entering said aperture, engaging said aperture, and a threaded nut engaging said threaded portion of said bolt and also engaging said insulating material.
20. A suspension-fixture, comprising a metallic member of substantially annular form and provided with apertures, means for supporting said metallic member, a bolt for supporting a clip, said bolt being provided with a shoulder and with a portion entering one of said apertures, and also provided with a mutilation, insulating material engaging said bolt and said last-mentioned aperture, and an insulating medium engaging said metallic member and also engaging said mutilation, thereby preventing movements of said bolt relatively to said insulation.
21. A suspension-fixture, comprising a metallic member of hollow form, means for supporting said metallic member, a revolute bolt connected with said metallic member and insulated therefrom, said revolute bolt being provided with a portion extending into 70 said metallic member, and insulation engaging said metallic member and said bolt so as to prevent relative movements between the same.
22. A suspension-fixture, comprising a metallic body portion provided with apertures, tubular metallic members disposed within divers of said apertures and out of contact with said metallic body portion, said tubular metallic members being in alinement with 80 each other, and insulating material engaging said tubular metallic members and also engaging said body portion for the purpose of insulating said body portion and said tubular members from each other.
23. A suspension-fixture, comprising a body portion provided with apertures, tubular metallic members provided with shoulders and disposed within divers of said apertures, insulating material engaging said body portion 85 and also engaging said tubular members for the purpose of insulating the same from each other, locking members for preventing the withdrawal of said tubular members from said apertures, and an insulating medium covering said locking member, said metallic member and portions of said tubular members.
24. A suspension-fixture, comprising a metallic body portion provided with apertures, tubular threaded metallic members disposed 90 within divers of said apertures and out of contact with said metallic body portion, said threaded tubular metallic members being in alinement with each other, and insulating material engaging said metallic body portion 95 and also engaging said tubular threaded metallic members for the purpose of insulating the same from each other.
25. A suspension-fixture, comprising a metallic body portion provided with apertures, 100 tubular threaded metallic members disposed within divers of said apertures, insulating material engaging said metallic body portion and also engaging said tubular threaded metallic members for the purpose of insulating 105 the same from each other, and an insulating medium covering said metallic body portion and portions of said tubular threaded metallic members.
26. A suspension-fixture, comprising a metallic body portion provided with apertures, tubular threaded metallic members provided with shoulders and disposed within divers of said apertures, insulating material engaging 110 said tubular threaded metallic members, and also engaging said metallic body portion for the purpose of insulating the same from each other, locking members for preventing the withdrawal of said tubular threaded metallic members from said apertures, and an insulating medium covering said locking member, said metallic body portion and portions of said tubular threaded metallic members.
27. A suspension-fixture, comprising a me-

- 5 tallic member provided with an aperture, means for supporting said metallic member, a bolt provided with a shoulder and disposed within said aperture for supporting a clip, insulating material engaging said aperture and said bolt, and a locking member for preventing the withdrawal of said bolt from said aperture.
- 10 28. A suspension-fixture, comprising a metallic member provided with an aperture and with means for suspending said metallic member, a bolt provided with a shoulder and disposed within said aperture for supporting a clip, insulating material engaging said aperture and said bolt, a locking member for preventing the withdrawal of said bolt from said aperture, and an insulating medium covering said locking member, said metallic member and a portion of said bolt.
- 15 29. A suspension-fixture, comprising an annular metallic member provided with a plurality of radially-disposed apertures, divers of which are arranged in alinement with each

other, supporting members engaging said apertures, thus arranged in alinement, and mechanism engaging another of said apertures and free to support a clip.

30. A suspension-fixture, comprising an annular metallic member provided with a plurality of radially-disposed apertures, divers of which are arranged in alinement with each other, supporting members engaging said apertures thus arranged in alinement, hanger mechanism engaging said apertures thus arranged in alinement and insulated therefrom, and mechanism engaging another of said apertures, said mechanism being free to serve as a clip-support.

In testimony whereof I have signed my name to this specification in the presence of two subscribing witnesses.

LOUIS STEINBERGER.
